CLAIM

The ornamental design for a combined decanter and stopper therefor, as shown and described.

DESCRIPTION

FIG. 1 is a front elevational view of a combined decanter and stopper therefor, showing my new design; FIG. 2 is a side elevation viewed from the left of FIG. 1, the opposite side being a mirror image thereof; FIG. 3 is a rear elevational view thereof;

FIG. 4 is a top plan view thereof;

FIG. 5 is a bottom view thereof; and

FIG. 6 is a fragmentary cross sectional view taken along the lines 6—6 of FIG. 3.
